ATTORNEY

UNITED STATES PATENT OFFICE.

CLARENCE R. CALLAWAY, OF LONG BEACH, NEW YORK, ASSIGNOR TO GURNEY ELEVATOR COMPANY, INC., OF HONESDALE, PENNSYLVANIA, A CORPORATION OF PENNSYLVANIA.

ELEVATOR-CONTROL MECHANISM.

Application filed March 31, 1922. Serial No. 548,288.

This invention relates to elevator control mechanism.

The invention more particularly pertains to the type of elevator control in which the stopping of the elevator car is automatically controlled through a "floor limit device" by the position of the car.

One method of working out such a control system involves the use of a connection between the floor limit device and a fixed point on the elevator car or other mechanism for actuating the floor limit device dependent on the actual position of the elevator car in its travel.

With such a structure, however, it has been found that the different weights carried by the elevator car will cause the car to stop short of or pass the floor landing.

This invention has for its object to provide an elevator control constructed and arranged to compensate automatically for variations in the weight of the load carried by the elevator car thereby insuring the stopping of the elevator at the desired level.

Further objects of the invention will appear from the following specification taken in connection with the drawings which form a part of this application and in which—

Fig. 1 is a diagrammatic view showing in elevation a representation of an elevator car and a control device and the connections for operating the control device. In this view it is assumed that the load on the elevator is normal.

Fig. 2 is a diagrammatic view similar to Fig. 1 but showing a load on the elevator less than the normal load and illustrating the operating means for the control device in the position taken with less than a normal load on the elevator and

Fig. 3 is a diagrammatic view similar to Figs. 1 and 2 but showing the elevator carrying a load heavier than normal and illustrating the parts in the position taken when operating with a heavy load.

The invention may be briefly described as consisting of adjustable means connected to the control device and automatically adjustable with respect thereto by the variations in the load carried by the elevator car.

At the outset it should be understood that the illustrations in the drawings are largely diagrammatic and are intended to illustrate

the principle of the invention rather than the actual structural details of elevator control mechanism.

Referring to the drawings, I have shown an elevator car 10 suspended from hoisting cables 11. A plate 12 is secured to the ends of the cables or to rods 13 suspended from the cables and springs 14 mounted on the rods 13 and are positioned between the plate 12 and the upper frame member 15 of the car. It will be seen therefore that the car is suspended from the cables through the intervention of the springs 14.

In Fig. 1 it is assumed that the load 16 is a normal load for the elevator and that the operating and actuating means for the control device about to be described will assume under operating conditions with the normal load 16, the relative positions shown in Fig. 1. A control device, known in the art, as a "floor limit device" is shown diagrammatically at 17 and this device is operated by means of an endless cable 18 which passes at its upper end around a sheave 19 and at its lower end around a sheave 20 to which is secured a weight 21 for the purpose of maintaining the cable 18 taut.

As is well known the purpose of the control device 17 or floor limit device is to stop the car at the desired floor or level when the operator has actuated the electric push buttons or other suitable mechanism for setting in operation the control device. However, it has been found that although such operating means is satisfactory when the car has a normal load, this mechanism alone is not sufficient to stop the car at the proper level when the weight carried by the car is less than or greater than the weight of the normal load. For example, when the car is making an up trip and the weight of the load is less than normal the car will stop above the floor level and on the down trip under the same load conditions the car will stop before it reaches the floor level. When the weight of the load is greater than normal the car will stop below the floor level both on the up and down trips.

In order to overcome this difficulty I have provided operating means for the control or floor limit device variable in position with the variations in the weight of the load

carried by the car. This means comprises an arm or lever 22 shown in the particular embodiment of the invention as pivoted at 23 to the car and having one end 24 connected to the cable 18 and its other end 25 connected by a rod 26 to the plate 12. A dash pot 27 is connected by a link 28 to the arm 22 to steady the arm and to dampen the fluctuations or movements of the arm about the pivot 23.

From the showing in Fig. 1, it will be seen that the arm 22 is substantially horizontal when a normal load 16 is carried by the car.

When, however, the load is less than normal as shown in Fig. 2, the plate 12 will be spaced a greater distance from the cross member 15 of the car or in other words the springs 14 will lift the car on the cables 20 or rods 13. This will cause the arm 22 to swing on its pivot 23 to the position shown in Fig. 2 thereby advancing the actuation of the floor limit device through an angle which may be diagrammatically represented 25 as the angle α in Fig. 2.

When the load carried by the car is greater than normal as shown in Fig. 3, the springs 14 will be compressed and the plate 12 will approach the frame member 15 and 30 the car thereby swinging the arm 22 downwardly about its pivot to a position such as that shown in Fig. 3. This will delay the actuation of the control device thereby insuring the stopping of the car at the desired floor level. The delay in the actuation of the floor limit device may be represented by an angle such as the angle β in Fig. 3.

Thus it will be seen that the control device is actuated sooner on the up trip and later on the down trip, with a light load and with a heavier than normal load the device will be actuated later on the up trip and sooner on the down trip.

From the above description it will be seen that simple and practical means has been provided for controlling the actuation of an elevator control or floor limit device in such a manner as to compensate for the variations in the weight of the load carried by the car and to insure the stopping of the car at the desired level.

Although for the sake of illustrating one practical embodiment of the invention, the parts have been diagrammatically shown as located in certain positions, it will be understood that the relative locations of the various parts may be changed without departing from the spirit or scope of the invention as expressed in the following claims.

What I claim is:—

1. In combination, a floor limit control device for an elevator, an elevator car, hoisting means connected thereto and means connected to said hoisting means, to the car and

to the floor limit device for automatically compensating for variations in the weight of the load on said hoisting means.

2. In combination, a floor limit control device including a sheave and a cable for an elevator, an elevator car, hoisting means connected thereto, and means connected to said hoisting means, to the car and to the cable of the floor limit device for automatically compensating for variations in the weight of the load on said hoisting means.

3. In combination, a floor limit device for elevator cars, an elevator car, operating means for said device including a cable, a lever pivoted on the car and connected to said cable, hoisting means for the car and compensating means between the lever and hoisting means whereby the actuation of the limit device is advanced or delayed as the weight of the load on the car is increased 85 or decreased with respect to a predetermined weight.

4. In combination, a floor limit elevator stopping device, an elevator car and operating means for said device, including a lever pivoted on said car, and a cable connected to said lever and operatively connected to said stopping device constructed and arranged to advance or delay the actuation of the device as the weight of the load on the car is decreased from or increased over a predetermined weight.

5. Elevator control mechanism comprising a floor limit control device and operating means for said device including a cable and pivoted means on said car automatically adjustable by the weight of and the weight carried by the elevator car to compensate for the variations in weight and insure the stopping of the elevator car at the desired 105 level, said pivoted means being connected to said cable.

6. In combination, a floor limit device for elevator cars, an elevator car, operating means for said device including a sheave geared to said limit device, an endless cable passing over said sheave, a lever pivoted on the elevator car and connected to said cable, hoisting means for the car and compensating means between the lever and hoisting means whereby actuation of the limit device is advanced or delayed as the weight of the load on the car is increased or decreased with respect to a predetermined weight.

7. An elevator car, a hoisting line yieldably connected to the car, and mechanism providing landing stops for the car and including a control drum, a line therefrom, and a lever connected to the lines and car.

8. A car, a hoisting line for the car yieldably connected to the car, a control line, and a hoisting line influenced connection for the control line to the car.

9. A car, a hoisting line yieldably con-

nected to the car for actuating the car, and a control line connected to the hoisting line.

10. A car, a hoisting line for the car yieldably connected to the car, a lever connected to the car and the hoisting line, and a control line connected to the lever.

11. A car, a hoisting line for the car yieldably connected to the car, a lever connected to the car, and a control line, said lever

having one arm connected to the hoisting line and a second arm connected to the control line, and said arms proportioned to affect the control line as the momentum due to car load changes is varied.

In witness whereof, I have hereunto set my hand this 8th day of February, 1922.

CLARENCE R. CALLAWAY.
